CHANNEL CEMENTING MACHINE

Thomas Lund, Beverly, Mass., assignor to United
Shoe Machinery Corporation, Paterson, N. J.,
a corporation of New Jersey

Application February 11, 1932, Serial No. 592,318

11 Claims. (Cl. 12—80)

This invention relates to channel cementing machines of the type shown in Letters Patent of the United States No. 1,778,184, granted October 14, 1930, upon the application of John W. Cosgrove, the illustrated machine being particularly adapted for operating upon the channels of rubber or composition soles preparatory to laying the channel flaps.

In the manufacture of certain styles of shoes, notably sport shoes, there is used a type of sole containing more or less vulcanized rubber which is attached to the shoe by stitching, and this stitching is sometimes done in a channel. The channel flap of such a sole has substantial resilience and will not stay back, and the cementing of these channels, in order that the flap may be securely attached to the sole, cannot readily be carried out by the use of machines of the type shown in the above-mentioned patent, where the cement is applied by means of a rotary brush, because of the difficulty in holding the channel flap open and of getting the brush well into the channel.

Accordingly, an important object of the invention is to provide an improved channel-cementing machine especially adapted for use upon channeled rubber soles and by means of which cement may be evenly applied to all portions of the channel including the inside of the channel flap. This object is attained by the use of a cementing machine organization including a cement applying device which is formed and adapted to push apart the channel flap and the body portion and to apply cement thereto. As illustrated, the machine includes a rotary applying member of special construction adapted to open the channel and to reach all portions thereof. As shown, this applying roll has a wedge-shaped periphery, to both faces of the sharpened portion of which cement is supplied in controlled quantities. Provision is also made in the illustrated machine for holding the channel flap firmly against the applying roll by means of an operator-controlled presser roll normally spring separated from the applying roll.

These and other features of the invention are more fully described in the following specification taken in connection with the accompanying drawing, in which

Fig. 1 is a side elevation of the working parts of the machine;

Fig. 2 is a front elevation of the applying roll and its surrounding casing; and

Fig. 3 is a plan view on a larger scale of the channel flap presser and its support.

A cement-applying roll 10 of disk shape is provided with a sharpened or wedge-shaped periphery 12 comprising opposed faces 13 and 14 which are knurled or roughened slightly to improve their cement-carrying capacity. This roll has a hub 16 slotted to engage a pin upon a driven shaft 18 journaled in a frame 20, the structure of which may be substantially or exactly like that shown in the Cosgrove patent to which reference has been made. This frame embodies a flattened horizontal arm 22 to the upper side of which there may be attached a suitable receptacle 24 having a delivery opening 26 communicating with a passage 28 in said plate. The flow of cement through the delivery opening 26 may be controlled by a valve 30. The under side of the arm 22 is provided with an undercut groove 32 for the reception of the complementary part of a slide 34 forming one side of a casing surrounding the applying roll 10 and coacting with the inner side face of the roll. Coacting with the outer side of the roll 10 is a wall 36 upon a scraper-carrying arm 38 adjustably secured to the slide 34 by means of a screw 40 passing through a horizontal slot in said arm 38, thereby enabling the position of the arm and the wall 36 carried thereby to be adjusted to correspond with the thickness of the roll 10. Carried upon this arm 38 is a scraper blade 42 provided with a V-shaped slot 44. This scraper 42 is attached to the arm 38 by screws 46, and the slot 44 is so designed that the scraper lies in close relation to the down-going side of the roll 10 rotated in a counter-clockwise direction as viewed from the front of the machine. The scraper therefore controls the quantity of cement taken out of the machine by the applying member, while the close relation of the casing formed by the slide 34 and the wall 36 to the ends of the roll prevents leakage of cement at these points. Because of the fairly heavy consistency of the rubber cement usually employed for such work, no special precautions against leakage need to be taken with respect to the up-going side of the roll so long as the roll is in motion, and the valve 30 may be closed when the machine is not in use.

The machine is illustrated as in use for the application of cement to the channel 50 and to the flap 52 of a rubber sole 54 to the upper surface of which there is secured a thin leather cover 56 which is cemented to the sole and is also secured thereto by a row of stitching 58. The sole 54 is shown as attached to the insole 60 and the upper 62 of a shoe by means of a row of stitching 64 positioned in a groove 66 formed near the

bottom of the channel 50. It is desired that the cement should be applied all the way to the bottom of the channel 50, thereby covering the stitches 64 and making sure of the firm adherence 5 of the channel flap 52. The sole 54 has sufficient rigidity so that the operator may readily press it against the outer face 13 of the wedge-shaped periphery of the roll 10. The sharpened periphery 12 of this roll facilitates its insertion in the channel 50, pushing aside the channel flap 52 and depositing cement all the way to the bottom of the channel. The shoe may be moved either with or against the direction of rotation of the roll 10 in accordance with the particular work and the desires of the shoe manufacturer. It is not desirable 15 that the surface of the roll 10 shall be unduly rough because of the abrading effect upon the rubber of the sole. On the other hand, it should not be absolutely smooth because of the "slipperiness" of the cement and the difficulty in obtaining 20 a uniform application of cement with such a roll.

The channel flap 52 is comparatively thin and, although it has a substantial resilience urging it toward the body of the sole 54, it nevertheless does not have sufficient rigidity or strength to insure its firm contact with the inner side 14 of the wedge-shaped surface of the applying roll across the whole width of the flap. Accordingly, there 25 is provided a presser roll 70 mounted for free rotation at the end of a lever 72 pivoted upon a screw 74 threaded in an arm 76 adjustably secured to the frame of the machine. A spring 78 surrounding an adjustable stop screw 80 threaded 30 in a flange 82 formed upon the arm 76 controls the relation of the pressure roll to the work and, in the arrangement shown, tends to move the presser roll away from the work and thus avoids any accidental contact of the presser roll with 35 the cement upon the applying roll when no work is being presented. The inner end of the lever 72 is connected by means of a chain 82 with a treadle 84 normally held in elevated position by means of a spring 86. Various adjustments of the 40 position of the presser roll 70 are provided by reason of the mounting of the arm 76. The end of this arm is turned at right angles and held against an angle iron 88 by means of a bolt 90 passing through horizontal slots in these parts. 45 The angle iron 88 is adjustably attached to the frame 20 by means of a thumb screw 92 passing through a horizontal slot in the frame. This arrangement provides for adjustment of the position of the presser roll 70 in two angularly related horizontal directions. The adjustment provided by the bolt 90 in a direction substantially 50 parallel to the line of feed is primarily for the purpose of insuring the correct position of the roll in setting up the machine, while the adjustment provided by the thumb screw 92 in a direction substantially parallel to the axis of the applying roll enables correct positioning of the presser roll toward and away from the face of the applying roll to accommodate channel flaps of 55 different thicknesses.

In the operation of the machine, as the shoe is presented to the machine, the sharpened periphery 12 of the applying roll enters the channel, pushing aside the channel flap 52, and the shoe 60 is held by the operator so that the channeled sole is in firm contact with the outer surface 13 of the applying roll. The shape of the applying roll enables it readily to enter all the way to the bottom of the channel as the shoe is moved horizontally with respect to the lower side of the ap-

plying roll in the customary manner. During this operation the channel flap 52 is pressed against the inner face 14 of the applying roll by means of the presser roll 70, operator-controlled through the use of the treadle 84. The stop screw 80 in the supporting bracket makes it easy for the operator to avoid undue pressure upon the flap. 5

Having thus described my invention, what I claim as new and desire to secure by Letters Patent of the United States is:

1. In a channel cementing machine, a receptacle having an outlet, an applying roll the periphery of which is wedge-shaped with adjacent cement-applying surfaces, said roll being rotatable in an upright plane and positioned below said outlet, means positioned for tight engagement with the lateral faces of said roll for preventing leakage of cement, and means in operative relation to the adjacent surfaces of said wedge-shaped periphery for controlling the delivery of cement to the work. 15

2. In a channel cementing machine, a cement-applying roll having a wedge-shaped periphery adapted to open up and to apply cement to the channel of a sole, means for supplying cement to both faces of the upper part of the periphery of said roll, a scraper having a wedge-shaped recess and controlling the quantity of cement on said faces, and means for holding a channel flap in engagement with one face of the wedge-shaped periphery near the bottom. 20

3. In a channel cementing machine, an applying roll having a wedge-shaped periphery adapted to open and apply cement to the channel and to the flap of a sole, means for supplying cement to the wedge-shaped periphery of said roll, movably mounted displaceable means adapted to be moved into contact with a channel flap for holding said flap against a face of the roll, resilient means tending to move said flap-holding means in one direction, and operator-controlled means for moving said flap-holding means in the opposite direction. 35

4. In a channel cementing machine, an applying roll having a wedge-shaped periphery adapted to open and apply cement to the channel and to the flap of a sole, means for supplying cement to the wedge-shaped periphery, displaceable means for holding the channel flap in engagement with the face of the roll, and operator-controlled means for moving said means against the flap. 45

5. In a channel cementing machine, an applying roll having a wedge-shaped periphery adapted to open and apply cement to the channel and to the flap of a sole, means for supplying cement to the wedge-shaped periphery, a displaceable roll adapted to be brought into contact with the channel flap to hold it in engagement with a face of said roll, resilient means tending to move said roll away from the cement roll, and operator-controlled means for moving said roll into engagement with the work. 55

6. In a machine for cementing channels in attached shoe soles, a cement applying roll having a portion exposed for the presentation thereto of an attached shoe sole, a pressure roll engaging a channel flap to hold it against the applying roll, and means for supporting said pressure roll for adjustment toward and away from the applying roll. 70

7. In a machine for cementing channels in attached shoe soles, a cement applying roll having a portion exposed for the presentation thereto 75

of an attached shoe sole, a pressure roll for holding a channel flap against the applying roll, and means for supporting said pressure roll for adjustment in a direction substantially parallel to the line of feed.

5. 8. In a channel cementing machine, a cement applying roll, a pressure roll engaging a channel flap to hold it against the applying roll, a pivoted support for said pressure roll, and a fulcrum for 10 said support adjustable in a direction toward and away from the face of the applying roll, thereby to accommodate flaps of different thicknesses.

10. 9. In a channel cementing machine, a cement applying roll, a pressure roll adapted to press the 15 channel flap against the face of the applying roll, a support, and a lever carrying said roll pivotally mounted on said support, said support being mounted for adjustment in a direction substantially parallel to the axis of the applying roll.

10. In a channel cementing machine, a cement applying roll, a pressure roll adapted to press the channel flap against the face of the applying roll, a support, and a lever carrying said roll pivotally mounted on said support, said support being mounted for adjustment in a direction substantially parallel to the direction of feed of the work.

11. In a channel cementing machine, a cement applying roll, a pressure roll engaging a channel flap to hold it in contact with a side face of the applying roll, an adjustable support, an arm carrying said pressure roll pivotally mounted on said support, and a spring interposed between said support and said arm acting upon said arm to control the relation of the pressure roll to the work.
